US00D694057S

(12) **United States Design Patent**
Shoshan

(10) **Patent No.:** **US D694,057 S**
(45) **Date of Patent:** **** Nov. 26, 2013**

(54) **ASSEMBLY FOR COOKING ELONGATED FOOD PRODUCTS**

(71) Applicant: **Marc Shoshan**, Hallandale, FL (US)

(72) Inventor: **Marc Shoshan**, Hallandale, FL (US)

(73) Assignee: **Kedem LLC**, Hallandale, FL (US)

(**) Term: **14 Years**

(21) Appl. No.: **29/454,725**

(22) Filed: **May 14, 2013**

(57) **CLAIM**

The ornamental design for an assembly for cooking elongated food products, as shown and described.

DESCRIPTION

FIG. 1 is a front perspective view illustrating my design for an assembly for cooking elongated food products;

FIG. 2 is a left side elevation thereof;

FIG. 3 is a front elevation thereof;

FIG. 4 is a right side elevation thereof;

FIG. 5 is a rear elevation thereof;

FIG. 6 is a top plan view thereof; and,

FIG. 7 is a bottom plan view thereof.

The broken/dashed-lined disclosures in the figures are for illustrative purposes only and form no part of the claimed design.

1 Claim, 4 Drawing Sheets
